UNITED STATES PATENT OFFICE.

WILLIAM B. McDONALD, OF BUFFALO, NEW YORK, ASSIGNOR TO JOHN G. WICKSER, OF SAME PLACE.

DESIGN FOR A RUBBER QUARTER-BOOT.

SPECIFICATION forming part of Design No. 26,691, dated February 23, 1897.

Application filed November 30, 1896. Serial No. 614,011. Term of patent 14 years.

To all whom it may concern:

Be it known that I, WILLIAM B. McDONALD, a citizen of the United States, residing at Buffalo, in the county of Erie and State of New York, have invented and produced a new and original Design for Rubber Quarter-Boots, of which the following is a specification, reference being had to the accompanying drawings, showing a part thereof.

10 This invention relates to a design for rubber quarter-boots for horses.

In the accompanying drawings, Figure 1 represents a vertical section of a quarter-boot embodying my design. Fig. 2 is a top plan view of the boot.

Like letters of reference refer to like parts in both figures.

The leading feature of my design consists of a boot which has a contracted neck portion and a downwardly-flaring body terminating in a somewhat thinner skirt and which has a continuous or unbroken surface circumferentially and throughout its height.

A represents the contracted tubular neck or top portion of the boot, which has at its 25 upper end a rounded circular rim *a*. B represents the tubular body portion of the boot, which flares downwardly from the neck portion and is considerably thicker than the latter. C represents the tubular skirt, which 30 depends from the body portion and is somewhat thinner than the latter. All of these parts are formed in one continuous piece without joint or break vertically and circumferentially, so that the boot presents an inner and 35 an outer surface, each of which is continuous or unbroken vertically and circumferentially.

I claim as my invention—

The design for a rubber quarter-boot herein shown and described.

Witness my hand this 27th day of November, 1896.

WILLIAM B. McDONALD.
